UNITED STATES PATENT OFFICE.

ALBERT C. HESSEL, OF NEW YORK, N. Y.

CONVEYER SYSTEM FOR STEAM AND OTHER SUBSTANCES.

1,308,072.

Specification of Letters Patent.

Patented July 1, 1919.

Application filed May 4, 1916. Serial No. 95,404.

To all whom it may concern:

Be it known that I, ALBERT C. HESSEL, a citizen of the United States, residing in the city, county, and State of New York, 5 have invented certain new and useful Improvements in Conveyer Systems for Steam and other Substances, of which the following, taken in connection with the accompanying sheets of drawings, is a full, clear, 10 and concise description.

In steam conveying systems as heretofore constructed it has been the common practice to provide T's preferably at equi-distant points in the run of the conduit for the accommodation of suitable frames which are employed to support the rods which, in turn, support the conveying pipes. The supporting frames are generally anchored in cement or concrete in the bases of the T's 15 with the upper portion of the framework extending into the bore of the conduit where it supports the cross rods in position to receive the conveying pipe.

It is one of the objects of my invention 20 to improve this system by avoiding the use of special T's and the supporting frames for the roller and pipe-carrying rods and thus not only cheapen the cost of installation of the system, but simplify it as well. 25 To accomplish this desideratum, I mount my pipe and roller-carrying rods at a point of juncture of adjacent sections of the conduit, and support the ends of said rods by the filler, which is provided between the 30 "bell" and "spigot" ends of said adjacent sections to provide an air and watertight joint.

A further object of my invention is to 35 provide a rigid or concrete supporting base for the conduit, preferably positioned at the point of juncture of adjacent sections, which will add support to the conduit where the weight of the steam pipes is received.

A still further object of the invention is 40 to provide a stress-distributing and supporting frame for the roller-pipe-carrying rods, positioned wholly within the conduit, and preferably supported by the filler between adjacent sections. These and other objects 45 of the invention will manifest themselves upon a reading and understanding of the following specification, in which—

Figure 1 is a fragmentary vertical cross-sectional view of a system incorporating

some of the above-specified novel features 55 of invention, the steam conveyer pipes being shown in side elevation.

Fig. 2 is a composite view representing in horizontal cross-section the system illustrated in Fig. 1, and the roller and pipe- 60 carrying rods as extending through the conduit into the concrete base structure.

Fig. 3 is a cross-sectional view taken on line a—a of the composite illustration of Fig. 2, showing certain of the pipe and 65 roller-carrying rods supported by the exterior concrete support and other of the rods supported in the cementitious filler between adjacent sections.

Fig. 4 is a cross-sectional view of a modification showing the larger of the conveying pipes beneath the smaller ones, the rods supporting the same being additionally supported by a frame which adds strength and stability to the structure as a whole. 70

Fig. 5 is a fragmentary cross-sectional detail taken on line b—b of Fig. 4.

Fig. 6 is a fragmentary cross-sectional detail illustrative of the manner in which the supporting rods may be connected so that 80 when the larger and heavier of the conveying pipes are positioned on top, the stresses may be more equally distributed between the rods and an increasing share thereof borne by the lower one. 85

Referring to Figs. 1 and 3, the conduit is sectional in character, in lengths of approximately three feet. Each section is divided on a longitudinal line into upper and lower semi-circular sections 1 and 2. The extremities of each section terminate in what are termed in the art "bell" and "spigot" ends 3 and 4, respectively, the bell and spigot ends of adjacent sections being joined together by a filler of cementitious material 90 5 all of usual and well-known construction. Extending crosswise of the conduit at the point of juncture between adjacent sections and supported by the filler 5 are the rods 6 and 7 upon which are mounted the rollers 100 8 and 9 which, in turn, support the conveying pipes 10 and 11.

In the preferable embodiment of my invention and where the larger of the conveying pipes occupy a position above the 105 smaller pipe or pipes, both of the rods 6 and 7 are positioned and supported below the top of and between adjacent lower semi-

circular sections 2, these being conveniently positioned before the top sections 1 are placed. It will be understood that the rods and rollers are positioned in the cementitious filler and the latter allowed to harden before the pipes are installed. In order to add supporting strength to the conduit at the point of juncture of two sections where the rods and the weight of the conveying 10 pipes is localized, I provide a supporting foundation or base of concrete or analogous material 12. This monolithic supporting base is preferably of such width as to extend some distance on either side of the 15 meeting "bell" and "spigot" ends of the adjacent sections and is preferably of such depth as to extend to the top of the lower sections of the conduit, thus affording a supporting foundation for the conduit 20 throughout that portion where the weight of the conveying pipes is received.

According to another phase of my invention I may, where found desirable, locate the pipe supporting rods at a point other 25 than between the ends of adjacent sections. That is to say, for example, I may perforate the conduit as at 13 in Figs. 2 and 3, and by making the rod longer, may have it extend into, and be supported by the monolithic concrete supporting base 12, which, in this instance, will be located at this point rather than at the point of juncture of adjacent sections.

Where the larger conveying pipes are supported above the lower one and in order to equalize and distribute the incident stresses throughout both rods, I provide what may be termed, an equalizing strap or member 14. This member 14 may consist of a rectangular steel or iron bar provided with perforations for the reception of the two rods. In this manner the lower rod will receive a portion of the weight and incident stress of the rod above.

45 In instances where it is desirable to position the larger of the conveying pipes below the smaller ones, where, by reason of the relative diameters of the pipes and conduits, the position of the upper supporting rods will be above the top of the bottom sections, and to facilitate installation, I provide a bracket or frame 15, which has the general curvature of the conduit and which is provided with anchoring lugs 16. This bracket is provided with openings to receive the extremities of the rods 6 and 7. The anchoring lugs 16 and the ends of the rods 6 and 7 are held in position between adjacent sections by the cementitious material 5, the cementitious material being banked, as it were, as shown more in detail in Fig. 5, so as to extend upwardly on both sides of the frame as well as beneath so as to afford substantial support thereto.

I may provide the adjacent edges of the 65 conduit with cut outs 17 into which the cement filler may enter so as to more efficiently secure the same and prevent relative movement or shifting of the respective parts.

While I have illustrated, by way of example, several preferable ways of embodying the features of the invention in practical form, I do not wish to be understood as limiting myself to the precise details of structure so illustrated and described as these 75 may be varied or changed without departing from the spirit and scope of my invention as defined by the following claims:—

Having thus described my invention, what I claim as new herein and desire to secure 80 by Letters Patent is:—

1. In combination with a sectional conduit provided with adjacent bell and spigot ends, a pipe supporting rod having its extremities disposed between the bell and spigot ends, 85 and a cementitious filler within said bell to permanently maintain said rod in supporting position.

2. In a system of the character described, the combination of a monolithic base, a conduit made up of sections, each section having a continuous wall, said conduit being supported by said base and adapted to contain a plurality of pipe lines, and means for supporting said pipe lines out of contact 95 with said conduit, whereby the weight of said pipe lines will be borne by said base.

3. In a system of the character described, the combination of a monolithic base, a conduit partially surrounded by said base and 100 supported thereby, and adapted to receive a plurality of pipe lines, rods positioned transversely of said conduit, and means for permanently anchoring the extremities of said rods between adjacent portions of said 105 conduit, said means consisting of a cementitious filler for effecting a joinder of the conduit sections with each other, and with said monolithic base, whereby the load of the supported pipes will be directly transmitted to said base and therethrough to the bed earth.

4. In a system of the character described, the combination of a base, a conduit formed of a plurality of upper and lower sections 115 supported by said base and adapted to receive a plurality of pipe lines, rods positioned transversely of said conduit, and means for permanently anchoring the extremities of said rods between the bell and spigot ends of said conduit members below the upper edge of the lower half of the conduit sections, said means consisting of a cementitious filler extending a distance on each side of the point of joinder of the lower 120 halves of the adjacent sections and filling the space between the spigot and bell ends, said cementitious filler forming a mono-

lithic base for supporting the lower peripheries of the sections whereby the load of the supported pipes will be directly transmitted to said base and therethrough to the bed 5 earth.

5. In a system of the character described, the combination of a monolithic base, a sectional conduit partially surrounded by said base and supported thereby, the said base 10 being extended adjacent to the point of joinder of the sections of the conduit, rods positioned transversely of said conduit and adapted to support a plurality of pipe lines, and a cementitious filler positioned within 15 the registering ends of the adjacent sections and amalgamating with said monolithic base, the ends of said rods being positioned within said filler whereby the stress of the pipes supported by said rods will be borne 20 directly by the monolithic base and transmitted therethrough to the supporting bed earth.

6. In a system of the character described, the combination of a sectional conduit, a 25 monolithic base for supporting the lower half of each section of said conduit, said base being positioned at the point of joinder of the registering ends of the adjacent sections, a plurality of rods positioned trans- 30 versely within said conduit for supporting a plurality of pipe lines, and means whereby the load of said pipe lines will be carried by said monolithic base, said means consisting of a cementitious filler applied within 35 the space between the registering ends of the adjacent conduit sections and amalgamating with said monolithic base, the ends of said pipe supporting rods being permanently anchored in said filler.

40 7. In a system of the character described, the combination of a sectional conduit each section having an unbroken wall, a supporting base positioned at the point of joinder of the registering ends of adjacent sections, 45 means disposed transversely of each section to provide a pipe supporting medium, and a cementitious material for effecting a permanent union between said means, the walls of the joined conduit sections and said support- 50 ing base, whereby a monolithic structure will be formed.

8. In a system of the character described, the combination of a sectional conduit, each section being composed of upper and lower 55 halves, a supporting base at the point of joinder of the registering ends of the lower halves of the adjacent sections, a rod disposed transversely of the lower half of each

section to form a pipe supporting medium, and means for effecting a permanent union 60 between the extremities of said rods, the lower half of the conduit sections and said supporting base, whereby a monolithic structure will be formed, said means consisting of a cementitious filler within the registering 65 ends of the adjacent conduit sections, which is united with said supporting base; the upper half of each conduit section being removable to afford access to the interior of the system.

70 9. In a system of the character described the combination of a conduit, means for supporting a plurality of pipe lines therein and out of contact therewith, whereby the load of said pipe lines will be imposed upon a section of the conduit, and a monolithic reinforcing and supporting base for said conduit section, the load of the pipes being transmitted through the conduit section to the monolithic base and thence to the bed earth. 80

10. In a system of the character described, the combination of a monolithic base, a conduit composed of registering sections, each section having a continuous wall, said conduit being supported by said base, means for 85 supporting a plurality of pipe lines within said conduit and out of contact therewith, whereby the load of said pipes will be carried by said base, said means comprising rods extending across said conduit, means 90 independent of said conduit and positioned therein to form mountings for said rods, said latter means having projections extending between the registering ends of adjacent 95 sections of said conduit, the said adjacent sections having registering cut out portions at their edges, and a cementitious filler lying within the registering ends and cut outs of said adjacent conduit sections to bind and interlock the sections together, said filler 100 uniting with the base, the projections of said mounting means being embedded in said filler, whereby a substantially monolithic structure will be produced.

11. In a system of the character described, 105 the combination of a sectional conduit and a monolithic base, said base forming a support and reinforcement for the wall of said conduit and means for carrying a plurality of pipe lines within the conduit and out of contact therewith, whereby the load will be carried by the reinforced portion of the conduit and transmitted therethrough to the monolithic base and to the bed earth. 110

ALBERT C. HESSEL.
